UNITED STATES PATENT OFFICE.

WILLIAM F. WRIGHT, OF LISBON, OHIO.

TRACK HANGER.

Application filed August 28, 1924, Serial No. 734,711. Renewed December 2, 1925.

To all whom it may concern:

Be it known that I, WILLIAM F. WRIGHT, a citizen of the United States, residing at Lisbon, in the county of Columbiana and

5 State of Ohio, have invented a new and useful Track Hanger, of which the following is a specification.

This invention relates to a hanger designed primarily for supporting the overhead tracks 10 or beams on which the trolleys of overhead conveying systems are adapted to travel.

Because of the many different arrangements of overhead beams to which the carrier system must be connected during installation, it has not been possible heretofore to provide a standard form of hanger which can be used with any kind of overhead beam or with a beam disposed at any angle relative to the trolley beam or track of the conveyor or carrier. Consequently the cost of 20 installation has been materially increased because of the necessity of preparing special hangers for many installations.

It is an object of the present invention to 25 provide hangers which can be carried in stock and the parts of which can be assembled in various ways so as to adapt the hangers for use in connection with different kinds of supporting beams and in connection with beams located at different angles 30 relative to the trolley beam or track.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 40 within the scope of what is claimed without departing from the spirit of the invention.

In the accompanying drawings the preferred form of the invention has been shown.

45 In said drawings

Figure 1 is a perspective view showing one application of the hanger constituting the present invention.

50 Fig. 2 is a perspective view showing another application thereof.

Fig. 3 is a perspective view showing a hanger arranged as disclosed in Fig. 2 but applied to a supporting I-beam.

55 Fig. 4 is a vertical transverse section through the hanger shown in Fig. 3.

Fig. 5 is a section on line 5—5, Fig. 4.

Fig. 6 is a perspective view showing another modified arrangement of the hanger.

Fig. 7 is a perspective view of a further arrangement.

Referring to the figures by characters of reference 1 designates two flat strips preferably of steel provided at desired intervals with holes 2 for the reception of bolts. Opposed angle members 3 are provided, each 60 of these members having an inturned lower edge portion providing a gripping jaw shown at 4. These angle members 3 are each provided with bolt holes 5 near the upper corners thereof and with an intermediate 70 bolt hole 6 located along the center line of the member but below the level of the bolt holes 5.

In addition to the strip 1 and the gripping members 3 there are provided supplemental plates 7 preferably formed of rolled steel and each having one end offset at an angle as shown at 8 to provide a jaw. These supplemental plates have openings 9 adapted to match corresponding openings in the 80 strips 1.

In Fig. 1 has been shown the usual arrangement of a supporting beam relative to a trolley beam or track, wherein the supporting beam A and the trolley engaging beam B are shown parallel to each other. With these parts thus positioned the supplemental plates 7 are not used. The strips 1 are extended to opposite sides of the beam A and fastened thereto by means of bolts 10 90 extending transversely through the beam. The lower ends of the strip 1 are brought together between the upper portion of the gripping member 3 and the jaws 4 of these members are placed at opposite sides of and 95 in engagement with the top flange of the I-beam B. The parts are held assembled by a bolt 11 which is extended through the openings 6 in the members 3 and through one of the holes 2 in each of the strips 1. 100 By tightening this bolt the jaws 4 will be caused to grip tightly upon the top flange of the I-beam and the said member 3 will be also caused to bind upon a strip 1 as shown. In those instances where the beam B is at right angles to the supporting beam A the gripping members 3 are positioned between the lower ends of the strip 1 as shown in Fig. 2. These gripping members are held together by parallel bolts 12 extended 105 through the openings 5 and are also extended over a third bolt 13 arranged within

110

an opening in the strip 1. Bolts 12 are adapted to rest on the bolt 13, and when tightened, will clamp the members 3 on the beam B and also upon the bolt 13. Bolt 13, when tightened, will clamp the strip 1 against the opposite edge portions of the members 3. Thus the two beams will be held properly assembled.

If the arrangement disclosed in Fig. 3 is to be utilized in connection with an I-beam C used as a supporting beam the supplemental plates 7 are interposed between the upper portions of the strips 1. The lower ends of these plates are fastened to the strips 1 by a transverse bolt 14 having nuts 15 thereon for engaging the inner sides of the plates 7 and there are additional nuts 16 upon the outer ends of the bolts for clamping the strips 1 and the plates 7 between nuts 15 and 16. The upper offset ends or jaws 8 of the plates 7 are adapted to lap the lower flanges of the I-beam C and to clamp against said beam. A transverse bolt 17 extends under the beam C and through the strip 1 and plates 7 and, when tightened, will bind the parts together securely.

If the I-beams C and B are parallel with each other as shown in Fig. 4, the members 3 are connected to the strip 1 in the same manner as disclosed in Fig. 1 while the supplemental plates 7 are attached to the strip 1 in the same manner as disclosed in Fig. 3 so that the offset ends 8 of the plates will engage and bind on the bottom flanges of the I-beam C.

Under some conditions it is necessary to attach the hanger to the bottom face of a supporting beam as shown, for example, in Fig. 7. Where this arrangement is followed the upper ends of the strips 1 are bent laterally to provide oppositely extending end portions 18 adapted to rest flat upon the bottom face of the beam D. The supplemental plates 7 are arranged under these oppositely extended portions 18 and fit in the angles formed thereby. Thus bolts 19 can be extended through the plates 7 and extensions 18 and into or through the beam C to securely hold the parts assembled. The lower ends of the strips 1 can be connected to the beam B either as shown in Figs. 1 and 7 or as shown in Figs. 2 and 3.

The arrangement shown in Fig. 7 can be used in connection with wood, concrete or other supporting beams.

Obviously the arrangements shown are those most generally utilized but it is to be understood that various other modifications can be utilized with the form of hanger disclosed.

What is claimed is:—

1. A hanger including strips having spaced bolt receiving apertures, separate oppositely disposed gripping members having beam engaging jaws, and means for detachably con-

necting said members to the strips, said means including a bolt for binding the jaws upon a beam interposed therebetween.

2. A hanger including opposed strips apertured for the reception of attaching bolts, opposed angle members having beam engaging jaws, and means for connecting the jaws to the strips, said means including a bolt for drawing the angle members toward each other to bind the jaws upon an interposed beam.

3. A hanger including strips having bolt receiving apertures, opposed angle members having beam gripping jaws, means for connecting the angle members to the strips, said means including a bolt for drawing the angle members toward each other to bind the jaws upon an interposed beam, supplemental plates each having an offset end, and bolts extending through the strips and supplemental plates for fastening them together and for attaching said strips and supplemental plates to a supporting beam.

4. A hanger including strips having bolt receiving openings, opposed angle members interposed between the strips and having beam engaging jaws, means connecting the angle members for binding the jaws upon an interposed beam, and means connecting the strips and extending between the angle members and under said connecting means of the members for holding the members assembled with the strips.

5. A hanger including apertured strips, angle members interposed therebetween, each of said members having a jaw, a bolt connecting the angle members to bind the jaws upon an interposed beam, and a bolt connecting the strips and extending under the bolt of the angle members to hold said members and strips assembled.

6. A hanger including apertured strips, angle members interposed between the strips, and oppositely disposed, each of said members having a beam engaging jaw, spaced bolts connecting the angle members for drawing them together and binding the jaws upon the interposed beam, and a bolt connecting the side strips and extending between the angle members for binding the strips upon the angle members and for supporting the bolts of the angle members.

7. A hanger including side strips having apertures, angle members having beam engaging jaws, means connecting the angle members to the side strips, said means including a bolt for drawing the angle members toward each other to bind the jaws upon the interposed beam, supplemental plates each having an offset end for engaging a supporting beam, and means for binding the supplemental plates upon an interposed beam and for fastening said plates to the side strips.

8. A hanger including apertured side

- strips, a pair of angle members each having a beam engaging jaw at one end, there being a pair of apertures in the apertured end portion of each angle member, and a third aperture in each angle member below the space between the pair of apertures.
9. A hanger including apertured side strips, a pair of angle members each having a beam engaging jaw at one end, there being
- 10 a pair of apertures in the apertured end

portion of each angle member, a third aperture in each angle member below the space between the pair of apertures, and supplemental plates apertured to match certain openings in the side strips, each supplemental plate having an offset end. 15

In testimony that I claim the foregoing as my own, I have hereto affixed my signature.

WILLIAM F. WRIGHT.
